The ornamental design for a pharmaceutical package, as shown and described.

DESCRIPTION

FIG. 1 is a top plan view of a pharmaceutical package showing our new design;

FIG. 2 is a front elevational view thereof;

FIG. 3 is a rear elevational view thereof;

FIG. 4 is a right side elevational view thereof; and,

FIG. 5 is a left side elevational view thereof.

The undisclosed bottom view is planar and unornamented.
